UNITED STATES PATENT OFFICE.

ZDENKO PODHRADSKY, OF ASTORIA, NEW YORK, ASSIGNOR TO H. R. MALLINSON CO. INC., OF NEW YORK, N. Y., A CORPORATION OF NEW YORK.

FABRIC-TRIMMING APPARATUS.

Application filed September 23, 1925. Serial No. 57,990.

The invention relates to fabrics woven with a design which requires certain portions of the material to be cut away and the remaining design to be closely trimmed to produce the finished product. Heretofore, the final cutting away of superfluous material to trim the edges of the design, which constitutes a delicate operation, has been performed by hand; this requires the use of highly skilled operators and is time consuming and adds considerably to the cost of the finished material. The object of the invention is to provide a novel apparatus whereby the required close trimming of designs of the aforesaid fabrics may be mechanically performed in an efficient and speedy manner, without requiring the attention of any specially trained operators. Other more specific objects will appear from the description hereinafter and the features of novelty will be pointed out in the claims.

In the accompanying drawings, which show an example of the invention without defining its limits, Fig. 1 is a diagrammatic section of the apparatus; Fig. 2 is a front elevation thereof; Fig. 3 is a horizontal section on the line 3—3 of Fig. 2; Fig. 4 is a fragmentary view showing certain of the elements of Fig. 3 in a different position; Fig. 5 is a fragmentary side elevation of the apparatus; Fig. 6 is a combination detail view illustrating a preferred form of tension bar included in the apparatus; Fig. 7 is a diagrammatic section showing another form of the apparatus and Figs. 8, 9, and 10 are face views of an example of the fabric which is operated on by the machine.

As shown in Figs. 1 to 5 inclusive, the apparatus or machine comprises a suitable supporting frame 15 on which an auxiliary frame 16 is mounted, said auxiliary frame 16 being provided with a bed 17 located in a predetermined position; it is preferred to have the bed 17 arranged either in an upright position as shown in Fig. 1 or in a plane inclined to this position in order to secure the most efficient operative results. Brackets 18 are fixed upon the bed 17 and constitute bearings for stud shafts 19 which

carry discs 20 and 20^a at their opposite ends respectively as shown in Fig. 5. Supporting members or bars 21 and 21^a have their opposite ends connected by means of crank pins 22 with the discs 20 and 20^a respectively, the arrangement preferably being such that said members 21 and 21^a are reciprocated in circular paths in opposite directions with respect to each other; upon their inner faces, the members 21 and 21^a are provided respectively with brushes or equivalent devices 23 and 23^a which partake of the reciprocating movements of said members 21 and 21^a. The reciprocation of the members 21 and 21^a and their brushes 23 and 23^a may be accomplished in any convenient manner as for instance by means of spiral gears 24 located upon intermediate portions of the stud shafts 19 and meshing with spiral gears 25 fixed upon a shaft 26. The latter, as shown in Fig. 2, may be journalled in bearings 27 mounted upon a frame 15 and in a bearing bracket 28 located apart from said frame 15 and is provided with a pulley 29 operatively connected, by means of a belt 30, with the pulley 31 of an electric motor 32 which constitutes the means whereby the shaft 26 and its associated elements are driven.

Tension bars 33 are mounted upon the bed 17 and are located in pairs upon opposite sides of the reciprocating paths of the brushes 23 and 23^a as shown in Figs. 1 and 5; the bars 33 are preferably of semi-circular form in cross-section and are transversely grooved as indicated at 34 in Fig. 6 or otherwise roughened for the purpose to be more fully described hereinafter.

The apparatus further includes a shearing mechanism whereby the trimming operation is performed as will be set forth more fully hereinabove; in the illustrated example, this shearing mechanism consists of a stationary knife 35 located upon the frame 15 and a shearing roller 36 mounted upon said frame in cooperative relation to said knife as shown in Fig. 1. The knife 35 and shearing roller 36 are located in operative proximity to a channel-iron 37 secured upon the frame 15,

the forward flange *a* of said channel-iron being preferably somewhat higher than the rear flange *b* thereof as shown in Fig. 1.

The shearing roller 36 may be driven in any suitable manner as by means of a belt 38 connected with a pulley 39 on the shearing roller shaft and with a pulley 40 carried by a suitably mounted countershaft 41 which in turn is driven through the medium of a belt 42 connected with the pulley of an electric motor 43 as shown in Fig. 1.

In addition to the parts so far described, the machine includes brackets 44 adapted to removably receive the trunnions 45 of a roller 46 on which the fabric 47 is wound in the form of a roll *c*. Fabric rolls 48, 49, and 50, are located at suitable points on the frame 15 to predetermine the path of movement of the fabric 47 before it reaches the brushes 23 and 23^a and additional rolls 51, 52, 53, and 54, are provided to direct the fabric 47 after it leaves the shearing mechanism; if desired, one or more tension bars 55 may be included in the machine at suitable points. A take-up roller 46^a is provided for re-winding the fabric 47 after it has been trimmed, the roller 46^a being driven, for instance, by means of a belt 56 which is connected with a pulley 57 located on a countershaft 58; the latter carries a second pulley 59 which is connected by means of a belt 60 with a pulley 61 fixed upon the countershaft 41 as illustrated in Fig. 1. To improve the operation of the machine and more specifically the feed of the fabric 47 a gear wheel 62 may be mounted upon the shaft of the roll 52 in mesh with a pinion 63 carried by the countershaft 58. It will be understood that the elements shown diagrammatically in Fig. 1 are suitably mounted in any conventional manner to provide the desired construction and arrangement.

The fabric 47 upon which the machine is designed to operate comprises a foundation material *d* upon which the design *e* is produced in the well-known way; the design is such that it covers only predetermined parts of the foundation material *d*, the latter at other parts being free from the design and visible so that the finished fabric presents the appearance of a design produced upon a background. In producing the design mechanically, the fibres or threads which produce the same extend across the inside surface of those portions of the foundation material *d* which in the final product are to be devoid of the design in question; it will be understood that in Figs. 8, 9, and 10 an example of the fabric is shown at various stages looking at the surface to be trimmed. The portions of the finished fabric which in the final product are to be devoid of design are indicated at *f* in Figs. 8, 9, and 10, and the fibres or threads which initially extend completely across said portions *f* are indicated

at *g* upon the left hand portion at Fig. 8; it will be understood that the fibres or threads *g* are disconnected and free from those portions of the material *d* which lie immediately beneath the same in Fig. 8. 70 These fibres or threads *g* are cut away either manually or mechanically to form a fringe of threads or fibres *g* in about the manner indicated at the right hand portion of Fig. 8, this operation, which may be termed the 75 initial trim, being easily performed and requiring no great amount of care or skill on the part of the operators.

The apparatus hereinbefore described is intended to perform the more difficult and 80 final trimming operation whereby the design is positively outlined by the removal of the fringe *g* and substantially all traces of the loose threads or fibres *g* are removed therefrom as indicated in Fig. 10. The fabric 85 47 in the condition shown, by way of example, at the right hand portion of Fig. 8 is rolled upon the roller 46 and the trunnions 45. If the character of the fibres or threads *g*' is such that they possess an inherent stiffness and tendency to lie flat and return to such condition when the initial trim has been completed, as indicated at the right in Fig. 8, the fabric 47 prior to being rolled on the roller 46 is damped to 90 an extent sufficient to impart to said initially cut fibres or threads *g*' the property of retaining an upright position relatively to the surface plane of the foundation material *d* as will appear more fully hereinafter. From 95 the roll *c*, the fabric passes about the rolls 48, 49, and 50, in sequence, as indicated in Fig. 1 and over the tension members 33 of the bed 17 and to the inside of the brushes 23; from the final member 33 the fabric 47 passes 100 at a sharp bend over the flange *a* of the channel-iron 37 beneath the roller 51 and over the tension bar 55 and shaft 41 and then to the roller 52. After passing about and between the rollers 52 and 53 and over the second tension bar 55, the fabric 47 passes about the roller 54 and is wound up on the take-up roller 46^a. It will be understood that the feeding of the fabric 47 through the machine is brought about by the action of 115 the feed rollers 52 and 53 and the take-up roller 46^a and that said fabric is under a tension during its travel from the roller 46 to the roller 46^a.

During such feeding of the fabric 47, the 120 brushes 23 are reciprocated in circular paths in opposite directions with respect to each other and are moved toward the bed 17 in an operative brushing movement and away from the same, by the action of the discs 20 and 20^a so that said brushes in those parts of their paths which lie nearest to the bed 125 17, develop a brushing action in the direction transversely of the travel of the fabric 47, the path of which may be said to be 130

tangent to the paths of said brushes; the latter preferably operate in alternate sequence. Thus, as the fabric 47 passes over the lowermost pair of tension members 33 in Figs. 1 and 5, with that surface of the fabric upon which the fibres or threads g^1 appear, facing said brushes, the brush 23^a will engage the surface of said fabric with a brushing action and accordingly will brush up those fibres or threads g^1 which at this stage point in a direction opposite to the brushing direction, so that said fibres or threads assume and retain the position indicated at g^2 in Figs. 1 and 5. After the fabric 47 has been thus acted on by the brush 23^a it will pass along and be acted on in a similar manner by the brush 23 so that any of the fibres g^1 which may have escaped the brushing action of the brush 23^a will be brushed into the upright position g^2 by the action of the brush 23; the arrangement is such that the fabric 47, as it is engaged by the brushes 23^a and 23 is flexed inwardly between the two pairs of tension members 33, and is thus engaged under a pressure by said brushes, whereby the brushing action of the latter is made positive and efficient. The roughened surface of the members 33 prevents displacement of the fabric thereon in the direction of the length of said members 33, by the brushing action of the brushes 23^a and 23. In this condition, said fibres or threads in the upright position indicated at g^2 are carried to the shearing mechanism and because of the sharp bend which the fabric takes at the flange a of the channel-iron 37 approach the knife 35 in a position substantially perpendicular to its cutting edge. As the feed of the fabric 47 continues the combined action of the shearing roll 36 and the knife 35 will shear off the projecting fibres or threads g^2 in close proximity to the boundaries of the design and thus will closely trim said design so that when the fabric has completely passed through the machine and wound up on the take-up roll 46^a, said fabric will have the appearance indicated in Fig. 9. The take-up roll 46^a with the partly trimmed roll of fabric thereon is then placed in the brackets 44 and the roller 46 or its equivalent is placed in the position previously occupied by the roll 46^a and the fabric again passed through the machine to trim off the remaining fibres or threads g so that at the end of this operation, the fabric is completely trimmed and the design e appears as in Fig. 10.

To avoid the necessity for passing the fabric 47 through the machine twice to complete the trimming operation, the arrangement shown in Fig. 7 may be utilized. This arrangement comprises in addition to the brushing and trimming mechanism shown in Figs. 1 to 5 inclusive an additional trim-

ming and cutting mechanism comprising a bed 17^a upon which tension members 33^a are mounted in the same way as in the form previously described and which are located in pairs upon opposite sides of brushes or their equivalent 23^b and 23^c. These brushes are mounted upon supporting members 21^b and 21^c respectively, the latter being connected with discs 20^b and 20^c respectively. The rotation of the discs 20^b and 20^c is brought about through the medium of the spiral gears 24^a meshing with spiral gears 25^a, the latter being carried by a shaft 26^a which is driven through the medium of a belt 30^a connected with a pulley 29^a upon the shaft 26^a and with the pulley 31^a of the motor 32. In this apparatus, the fabric 47, after it leaves the roller 51 travels about rollers 64 and 65 and then over the tension members 33^a to the cutting mechanism. The latter comprises a knife 35^a and a shearing roller 36^a, the latter being connected by means of a belt 38^a with the shearing roll 36. A belt 38^b connects the shearing roll 36^a with a source of power such as a motor 43 as diagrammatically indicated in Fig. 7. A channel-iron 37^a is provided in close proximity to the knife 35^a over the forward flange a' of which the fabric travels to the roller 51^a and from thence over the tension bar 55^a; after leaving the latter, the fabric may traverse a path corresponding to the path of the fabric shown in Fig. 1 after said fabric leaves the tension bar 55 therein. It will be understood that in the arrangement shown in Fig. 7, the brushes 23^b and 23^c perform their brushing functions preferably in alternate sequence in directions opposite to the brushing action of the brushes 23 and 23^a. Thus, after the fabric 47 has passed the brushes 23 and 23^a and the cutting mechanism 35, 36, and 37 whereby some of the fibres or threads g^1 in the position indicated at g^2 are trimmed away, said fabric in continuing its course passes into operative relation to the brushes 23^b and 23^c. These latter brushes raise those fibres or threads g^1 which have not been trimmed away to positions perpendicular to the face of the fabric as indicated at g^3 so that these fibres or threads g^1 are in a position to be efficiently cut away by the action of the shearing mechanism 35^a, 36^a, and 37^a. Under such condition, as the fabric is finally wound upon the take-up roll 46^a or its equivalent, it will immediately be in the condition shown in Fig. 10 of the drawings without requiring said fabric to be passed through the machine a second time in reversed relation.

The machine is extremely simple in construction and performs the operation of trimming the design closely and effectively in a rapid and accurate manner without requiring the attention of any skilled opera-

tors and without danger of injury to the particular fabric, which ofttimes is of a very delicate nature.

Various changes in the specific form shown and described may be made within the scope of the claims without departing from the spirit of my invention.

I claim:

1. A trimming machine comprising a bed, feeding mechanism for feeding a web of fabric over said bed, said fabric including a design the outlines of which are bounded by loose thread ends, brushes moving to and from said fabric and transversely thereof effective upon said fabric to raise said loose ends to upright positions thereon and cutting mechanism in the path of said fabric for cutting away said upright loose ends to closely trim the aforesaid design along its outlines.
2. A trimming machine comprising a bed, feeding mechanism for feeding a web of fabric over said bed, said fabric including a design the outlines of which are bounded by loose thread ends, a brush movable as a unit to and from said fabric in an orbital path to sweep said fabric transversely thereof and effective upon said fabric to raise said loose ends to upright positions thereon and cutting mechanism in the path of said fabric for cutting away said upright loose ends to closely trim the aforesaid design along its outlines.
3. A trimming machine comprising a bed, feeding mechanism for feeding a web of fabric over said bed, said fabric including a design the outlines of which are bounded by loose thread ends, a pair of brushes each movable as a unit to and from said fabric in an orbital path to sweep said fabric transversely thereof, said brushes being successively effective upon said fabric to raise said loose ends to upright positions thereon and cutting mechanism in the path of said fabric for cutting away said loose ends to closely trim the aforesaid design along its outlines.
4. A trimming machine comprising a bed, feeding mechanism for feeding a web of fabric over said bed, said fabric including a design the outlines of which are bounded by loose thread ends, a first pair of reciprocating brushes successively effective upon said fabric to raise those loose ends which point in one direction, to upright positions on said fabric, cutting mechanism in the path of said fabric for cutting away said upright loose ends to closely trim the aforesaid design along parts of its outlines, a second pair of reciprocating brushes successively effective upon said fabric to raise those loose ends which point in the opposite direction, to upright positions on said fabric and additional cutting mechanism in the path of said fabric for cutting away the last named up-
- right loose ends to closely trim the aforesaid design along the remainder of its outlines.
5. A trimming machine comprising a bed, tension members fixed thereon and having roughened surfaces, feeding mechanism for feeding a web of fabric across said bed in contact with said tension members, said fabric including a design the outlines of which are bounded by loose thread ends, elements adapted to brush transversely of the fabric, said tension members being immediately adjacent said brushing elements, all cooperating to raise said loose ends to upright positions on said fabric and cutting mechanism in the path of said fabric for cutting away said upright loose ends to closely trim the design along its outlines.
6. A trimming machine comprising a supporting frame, a bed thereon, tension members fixed on said bed and provided with transversely grooved surfaces, feeding mechanism for feeding a web of fabric across said bed in contact with said tension members, said fabric including a design the outlines of which are bounded by loose threads, discs rotatably mounted on said frame in cooperating pairs, carrying bars eccentrically connected with each pair of discs, brushes mounted upon said bars, mechanism for rotating said discs whereby said brushes are reciprocated in circular paths and effective upon said fabric between said tension members to raise said loose ends to upright positions on said fabric and cutting mechanism in the path of said fabric for cutting away said upright, loose ends to closely trim the design along its outlines.
7. The method of trimming fabrics having designs with bordering thread ends, which consists in feeding the fabric, as the feeding progresses brushing in one direction some of the bordering thread ends to upright retained positions with respect to the surface of the fabric, trimming away said upright threads as the feeding of the fabric progresses, thereafter brushing the remaining bordering thread ends in another direction to upright retained positions with respect to the surface of the fabric and likewise trimming away said last named upright threads.
8. The method of trimming fabrics having designs with bordering thread ends which consists in feeding and tensioning the fabric over supports, brushing said fabric in one direction transversely of the direction of the travel of the fabric to raise some of the bordering threads to upright position, thereafter shearing said thread ends, and subsequently brushing the fabric in the other direction transversely of the direction of travel of the fabric to raise the rest of the thread ends to upright position and thereafter shearing said last named thread ends.

9. A trimming machine for fabric having a design with bordering thread ends comprising means extending transversely of the path of the fabric for feeding and applying longitudinal tension to said fabric, transversely extending supporting members for said fabric, a brush between and closely adjacent said supporting members movable

in an orbit in a plane transverse to the direction of travel of said fabric for raising said bordering thread ends to an upright position, and trimming means for said bordering thread ends. 10

In testimony whereof I have hereunto set my hand.

ZDENKO PODHRADSKY.
